APPARATUS FOR HEAT-TREATING
MINERAL MATERIAL

Joseph V. Slavick, Albuquerque, N. Mex., assignor
of three-fourths to Howard D. White, Chi-
cago, Ill.

Application December 2, 1949, Serial No. 130,744

2 Claims. (Cl. 209—11)

1

My invention relates to apparatus for expanding perlite and for the heat treatment of other mineral material.

An important object of the invention is to provide an apparatus of the above mentioned character which is relatively simple, cheap to manufacture, and which may be operated by a minimum of attendants.

A further object of the invention is to provide apparatus of the above mentioned character which will first separate out the large particles and then separate out from the discharging gases the small particles.

A further object of the invention is to provide apparatus of the above mentioned character which may be constructed substantially gas-tight to prevent the fumes from escaping in proximity to the attendants.

A further object of the invention is to provide a method which may be employed to quickly and economically heat treat the divided solid mineral material.

In the accompanying drawings, forming a part of this application, and in which like numerals are employed to designate like parts throughout the same,

Figure 1 is a central vertical longitudinal section through the apparatus embodying my invention,

Figure 1a is a fragmentary central vertical section through the upper end of the hopper, pre-heating pipe and associated elements;

Figure 2 is a transverse vertical section taken on line 2—2 of Figure 1;

Figure 3 is a horizontal section taken on line 3—3 of Figure 1, looking downwardly;

Figure 4 is a transverse section taken on line 4—4 of Figure 1;

Figure 5 is a front end elevation of the furnace, parts broken away;

Figure 6 is a horizontal section taken on line 6—6 of Figure 1, looking downwardly;

Figure 7 is a horizontal section taken on line 3—3 of Figure 1, looking upwardly;

Figure 7' is a central vertical section through a second form of heating chamber;

Figure 8 is a similar view through a third form of heating chamber; and

Figure 9 is a similar view through a fourth form of heating chamber.

The apparatus comprises a separating unit 10, including a horizontally elongated vertical casing 11 having an upper horizontal top 12. This casing includes a downwardly tapered portion 13 which terminates at its bottom in a trans-

2

versely circular curved trough 14. This trough is offset laterally with respect to the central longitudinal axis of the casing 11. The casing 11 is supported by posts or uprights 15.

5 The casing 11 is provided at its top and rear end with a discharge opening 16, extending throughout its entire width, and this discharge opening leads into a vertical flue chamber 17 projecting above the top 12 and continuing as a vertical stack or leading into a vertical stack. The vertical flue chamber 17 has a downwardly tapered lower portion 18, Figure 2, leading into a vertical flue 19, disposed at the transverse center of the casing 11. The trough 14 is offset laterally with respect to the flue 19 and is arranged upon one side of the same, as shown. The trough 14 is connected at its discharge end with a conveyor tube 20, surrounded by a water jacket 21, to cool the same. The trough 14 and tube 20 forming an extension of the trough are horizontally arranged and receive a horizontal spiral conveyor 22, which feeds the material from the trough to the outlet end 23 of the tube 20 to discharge the same into a bag 23' or the like. The spiral conveyor includes a shaft 24, the ends of which are journaled in bearings formed in spiders 25, one spider is arranged at the closed end of the trough 14, while the other spider is arranged adjacent to the outlet end 23 of the tube 20. The spiral conveyor 22 is driven by any suitable means, as by a motor 26 connected with the shaft 24 by suitable gearing 26.

The lower end of the flue 19 leads into a water holding tank 27 and has its discharge end arranged beneath the level of the water therein. It might be stated at this point that the fine solid particles recovered from the flue gases drop through flue 19 and are collected in the water in the tank 27. Water is circulated in the tank 27 by means of a pump 28 withdrawing the water from the tank through a pipe 29 and returning the water into the tank through a pipe 30. The finely divided solid material floats to the surface of the water and is removed from such surface by an endless belt 31 engaging rollers 31', 32' and 33'. This belt travels near and beneath a bank 32 of infra-red lamps which dry the solid particles. These solid dried particles are discharged to a point where they may be received 50 in a bag 33 or the like.

The top 12 is equipped with spaced transverse depending baffles 34 and 35. Baffle 34 is ordinarily longitudinally straight, while the baffles 35 are horizontally V-shaped. Baffle 34 is located a considerable distance from the sides of the air

ing 11, while the baffles 35 terminate close to the sides. Each baffle is vertically tapered downwardly, Figure 4.

A transverse horizontal pipe 36 is arranged within the casing 11 near and beneath the top 12 and adjacent to the opening 16 and has a longitudinal group of spaced spray nozzles 37, which face toward the stack chamber 17 and are disposed at an angle of about 30 degrees from the horizontal. These spray nozzles spray water into the ascending heated gases to wet the solid fine perlite particles, causing them to drop down by gravity through the lower flue 19. Water is supplied to the horizontal pipe 36 under suitable pressure in a continuous manner by any suitable means.

The apparatus comprises a furnace unit 38. This furnace unit includes a substantially vertical long heating chamber 39, which is rectangular in horizontal cross-section and is preferably the same width as the casing 11. This heating chamber is wide transversely of the casing 11 and relatively narrow longitudinally of the casing. This vertical heating chamber has its upper end open and discharging into a coupling 40, the top of which is preferably rounded. This coupling leads into the intake end of the casing 11. The bottom of the coupling is in the form of inclined walls 41 and 42, preventing the solid material from accumulating thereon. The sides of the heating chamber 39 diverge downwardly from points 43 and the diverging side portions 43' may be enclosed in brick walls 44 or other refractory material. If desired, the chamber 39 may terminate at the top of the brick walls 44 which will be built to form a vertical passage corresponding to the shape of the lower downwardly diverging end of the heating chamber 39.

A burner is provided to supply products of combustion into the lower end of the chamber 39. This burner comprises a horizontal pipe 45 having vertical burner elements 46 secured thereto. The flames from the burner elements 46 discharge upwardly into the heating chamber 39. The pipe 45 is connected with an air blower 47 to supply air under suitable pressure to the pipe 45, and gas is supplied to the pipe 45 from a pipe 48. The proper mixture of air and gas is provided by the pipe 48 and blower 47 and this mixture is supplied to the burner elements 46. Any desired gas may be used as fuel and the mixture of air and gas can be regulated as is found advantageous.

Arranged in contact with the outer side of the heating chamber 39 is a hopper 49, discharging into a vertical preheating pipe 50, in contact with the heating chamber 39. The inner side of the pipe 50 is formed by the outer side of the chamber 39. The pipe 50 is rectangular in cross-section and is preferably of the same width as the heating chamber 39. The preheating pipe is provided at its lower discharge end with an inclined bottom or lip 51 extending through an opening 52 in the outer side of the chamber 39 and projecting into the chamber 39. The bottom 51 is arranged above the points 43. A heat insulating jacket 53 encloses the heating chamber 39 and preheating pipe 50.

The bottom of the hopper 49 is covered by a horizontal reciprocating bar valve 54, the ends of which slide within openings 55 formed in the ends 50' of the pipe 50. The bar valve extends outwardly beyond the hopper for a short distance so that its ends remain within the opening 55 during the stroke of the bar valve. The bar

valve slides upon stationary supports 56. The bar valve is provided with a straight longitudinal group of spaced openings or apertures 57, which may vary in size, and may be one-fourth of an inch, three-eighths of an inch, or five-sixteenths of an inch in diameter, or other diameters. The purpose of the bar valve is to effect a continuous, even feeding of the divided material in the form of a curtain. Arranged beneath the bar valve 54 and rigidly secured thereto, is an inclined plate 58, slightly shorter than the width of the preheating pipe 50 so that it will not interfere with the stroke of the bar valve. The solid particles passing through the openings 57 fall upon the inclined belt 58, reciprocating with the bar valve whereby these particles are discharged downwardly in the form of a curtain. The bar valve is reciprocated by means of a rod 59 secured thereto and this rod has pivotal connection with a link 60, pivoted to a crank 61 rotated by a motor 62. It is thus seen that the motor will reciprocate the bar valve.

In the first form of the invention, the heating chamber 39 has the same width transversely of the casing 11 throughout the entire length of the chamber 39 but its sides 43' diverge downwardly, as shown.

In Figure 7', I have shown a heating chamber 63 to be used in place of the heating chamber 39. This heating flue 63 is identical with the chamber 39 except that its sides 63' are parallel through their entire length.

In Figure 8, I have shown a heating chamber 64 to be used in place of the chamber 39. This chamber 64 is identical with the chamber 39 except that its sides 64' diverge upwardly from its bottom to points 65 and then converge upwardly to points 66.

In Figure 9, I have shown a further modified form of heating chamber to be used in place of the heating chamber 39. This chamber is designated by the numeral 67 and is identical with the chamber 39 except that its sides 67' are provided with opposed inwardly projecting shoulders 68. All heating chambers have inlet openings 52 and all other parts of the apparatus remain identical.

The operation of the apparatus is as follows: When the apparatus is used for the heat treatment of perlite, the perlite rock is crushed or divided. Satisfactory results are obtainable by having the largest particles of the crushed perlite rock one-fourth of an inch in size, and smaller or finer particles also are produced by the crushing. The perlite rock may be crushed to smaller sizes and may be ground to substantially a powder. The crushed or divided perlite containing the large and small particles is introduced into the hopper 49, which is maintained substantially filled with this material. The burner device is set into operation and the heated gases or products of combustion from the burner elements discharge into the heating chamber 39 and travel upwardly therein and pass through the coupling 40, through the top of the casing 11 and through the opening 16 into the flue chamber 17. The burner device is regulated to heat the interior of the heating chamber 39 from 1600° F. to 2600° F., required to properly volumetrically expand the perlite. While the burner device is thus operating, the bar valve 54 is reciprocating and the divided perlite agitated and fed in a regulated manner through the openings 57, which are of sufficient size to permit of the passage of the largest particle. The perlite particles pass

through the openings in the bar valve in the form of a curtain, and fall against the inclined plate 58 and fall into the preheating pipe 50 in the form of a curtain, descend therein, and strike against the inclined bottom 51 and slide from this bottom into the heating chamber 39. The perlite particles are preheated before entering the heating furnace 39, which aids in their expansion. The perlite particles are fed into the heating chamber 39 in the form of a curtain and as soon as these particles enter the heating chamber 39, they are acted upon by the heat therein, from 1600° F. to 2600° F., and are instantly expanded volumetrically. One cubic foot of the divided perlite material weighs approximately 80 pounds, but after it is expanded, one cubic foot weighs only 6 to 16 pounds. The divided expanded perlite now passes upwardly with the upwardly ascending hot gases or products of combustion in which it is suspended. The expanded divided perlite material or particles which vary in size, now pass from the top of the heating chamber 39 and enter the top of the casing 11, and travel horizontally therein. The larger particles strike against the baffles 34 and 35, which arrest their horizontal travel and cause them to drop by gravity and pass to the trough 14, from which they are removed by the screw conveyor. The smaller or lighter particles which are not thus separated out from the heated gases continue to travel with the gases and pass with them through the opening 16 and enter the flue chamber 17. As the heated gases and fine particles move upwardly in the flue chamber 17, the water spray from the nozzles 37 wets the fine perlite particles which are rendered heavier and they drop down through the flue 19 into the tank 27. These wet particles tend to float upon the upper surface of the water in the tank and are removed from such surface by the belt 31 and dried as they pass beneath the bank of infra-red lamps 32. The removed fine particles are carried by the conveyor to a bag or the like.

While I have shown and described the apparatus in the practice of the method for treating divided perlite, it may be used to expand and calcine pumice. Fine particles of lime also may be calcined by passing the same through the apparatus, as described in connection with perlite.

The heating chamber and other parts of the apparatus may be made of a heat resistant alloy or any suitable refractory material.

It is to be understood that the form of the apparatus herewith shown and described is to be taken as a preferred example of the same and that various changes may be resorted to in the shape, size and arrangement of parts, and that changes may be resorted to in the steps of the method, without departing from the spirit of the invention or the scope of the subjoined claims.

Having thus described my invention, I claim:

1. Apparatus for expanding and collecting the expanded perlite comprising a wide horizontal casing having a substantially greater length than width, said casing including a top, sides and ends, one end being provided at the top with an inlet opening extending for substantially the entire width of the casing and the opposite end being provided at the top with an outlet opening extending for substantially the entire width of the casing, said casing including a downwardly tapering lower portion including sides arranged at a steep angle so that the expanded perlite

being provided at its bottom with a trough extending longitudinally of the casing throughout the major portion of the length of the casing, a substantially vertical inlet heating chamber extending for substantially the entire width of the casing and the inlet opening and leading at its upper end into the inlet opening of the casing and having its top vertically inclined inwardly and longitudinally of the casing to direct the expanded perlite material horizontally through the inlet opening and casing, means for supplying the divided perlite and heated gases into the heating chamber throughout substantially the entire width of the heating chamber, transverse baffles arranged upon the inner face of the top of the casing and extending throughout substantially the entire width of the casing, said baffles being arranged in a longitudinal group extending throughout the entire length of the casing and throughout the entire length of the trough, the arrangement being such that the light expanded perlite will be separated out from the hot gas stream by the baffles and will be conducted to the trough without liability of clinging to parts of the casing, and a conveyor operating within the trough to remove the solid expanded perlite.

2. Apparatus for expanding and collecting the expanded perlite comprising a wide horizontal casing having a substantially greater length than width, said casing including a top, sides and ends, one end being provided at the top with an inlet opening extending for substantially the entire width of the casing and the opposite end being provided at the top with an outlet opening extending for substantially the entire width of the casing, said casing including a downwardly tapering lower portion including sides arranged at a steep angle so that the expanded perlite will slide downwardly thereon, said lower portion being provided at its bottom with a circularly curved trough extending longitudinally of the casing throughout the major portion of the length of the casing, a substantially vertical inlet heating chamber extending for substantially the entire width of the casing and the inlet opening and leading at its upper end into the inlet opening of the casing and having its top vertically inclined inwardly and longitudinally of the casing to direct the expanded perlite material horizontally through the inlet opening and casing, means for supplying the divided perlite and heated gases into the heating chamber throughout substantially the entire width of the heating chamber, transverse baffles arranged upon the inner face of the top of the casing and extending throughout substantially the entire width of the casing, said baffles being arranged in a longitudinal group extending throughout the entire length of the casing and throughout the entire length of the trough, the arrangement being such that the expanded perlite will be separated out from the hot gas stream by the baffles and will be conducted to the trough without liability of clinging to parts of the casing, a vertical flue chamber extending throughout substantially the entire width of the casing and disposed at the end of the casing having the discharge opening for communication with said discharge opening, a depending flue connected with the lower end of the flue chamber at its transverse center, the trough being offset laterally with respect to the flue to be disposed upon one side of the flue, an outlet tube disposed upon one side of the flue and connected with the discharge end of the trough and arranged in an

end-to-end relation with the trough, a common spiral conveyer operating within and extending throughout the combined length of the trough and tube, means for spraying water into the flue chamber adjacent to the discharge opening, and means for collecting material discharging from the lower end of the flue.

JOSEPH V. SLAVICK.
